JOSEF GASSEN, OF DUSSELDORF, GERMANY, ASSIGNOR TO SCHLOEMANN AKTIENGESELLSCHAFT, OF DUSSELDORF, GERMANY, A CORPORATION OF GERMANY

COOLING MEANS FOR ROLLED BARS

Application filed July 12, 1932, Serial No. 622,080, and in Germany July 13, 1931.

My invention relates to cooling devices for the cooling of rolled bars, and has particular reference to improvements in cooling beds, on which the rolled bars are successively moved along either singly, or in groups.

The object of the present invention is to produce a cooling device whereby rolled bars of any cross-section are gradually cooled especially when passing through the critical temperatures. In this way, rolled products of high quality are obtained. My cooling device is so designed and constructed that rolled flat bars having a large surface may be gradually cooled, which object I attain in providing special means permitting the bars to successively glide down an inclined plane to a place where they are arrested to be subsequently stacked and moved across the cooling bed in stacked formation, whereby all the bars are gradually and uniformly cooled, until they reach the place at the end of the cooling bed where they are removed. In this way, warping of the flat bars is effectively prevented.

The means permitting the downward glide of the flat bars are so arranged that they can be moved to operative and inoperative positions at will. In the latter event, the cooling device is arranged for the intermittent movement of rolled bars of other than flat cross-section toward the cooling bed by means of a step-shaped connecting member, on which the rolled bars are constantly supported. Operatively associated with said connecting member are lifting elements for moving the bars one step at a time. These lifting elements are disconnected, when flat bars are cooled.

The invention is shown on the annexed drawings, on which Fig. 1 is a side elevation of the new device, the central portion of the cooling bed being shown broken away and certain portions being shown in section; Fig. 2 is a similar view as Fig. 1 showing additional elements for adapting the device for the handling of rolled flat bars; Fig. 3 shows, on an enlarged scale, the right-hand part of Fig. 1 adapted for the handling of rolled bars of various cross-sections, the lifting elements being shown in their various operative

positions as indicated by the broken lines; Fig. 4 shows, on an enlarged scale, the right-hand part of Fig. 2 to more clearly illustrate the manner of operation in the handling and stacking of rolled flat bars; Fig. 5 is an enlarged detail view of that part of the device, where the flat bars are stacked.

In all the figures, at 1 is shown the feed-roller mechanism, at 2 the roller delivery bed, at 3 the removal device, at 4 the cooling bed, over which the rolled bars are transported without being lifted, and at 5 a mechanically driven rock-shaft extending longitudinally of the device and having mounted thereon the lever arms 6 and 7 which can be selectively coupled with or uncoupled from shaft 5.

The lever arms 6 have linked with them lifting elements 8 provided with vertical slots 9 which are engaged by the free ends of guide-levers 10 mounted on a longitudinally extending mechanically driven rock-shaft 11.

The lever arms 7 shown in Figs. 2 and 4 have linked to them supporting rods 12 carrying stacking elements 13 also acting as chutes. At 14 is shown a longitudinal beam and at 15 a longitudinally extending bracket provided with an inclined face acting as a chute. On these two elements rests a stepped plate 16 formed with a plurality of grooves 17 (Fig. 3), which are used for the handling of rolled bars of various cross-sections.

The operation of the above described device is as follows:

At 18 in Figs. 1 and 3 is shown a bar which in well-known manner is lifted out of the feed-roller mechanism 1 and on the inclined face of bracket 15 slides into the position indicated at 18'. Thereupon, by means of the lever arms 6 the lifting elements 8 linked to these lever arms are lifted from their position shown at I in Fig. 3 to the position shown at II and immediately thereafter, the lifting elements are swung by the guide-levers 10 mounted on shaft 11 and engaging in the slots 9 of the lifting elements 8 to the position shown by the broken lines marked III in Fig. 3 and by a corresponding rocking movement of shaft 5 are lowered to the position marked IV in Fig. 3 from which position the lifting elements 8 are returned by

the guide-levers 10 to their original position. Thereby a cycle is completed, and the rolled bar 18 has been carried from its position 18' (Fig. 1) to the position marked 18². By similar cycles of operation, the bar is successively carried to the position marked 18³ on the cooling bed 4, on which the bars are gradually moved along, either singly or in group, being cooled thereby. The delivery of the 10 cooled bars which have arrived at the roller delivery bed 2 shown at the left in Figs. 1 and 2 is effected in well-known manner by the removal elements shown at 3 in said figures, which elements, after each cycle, remove a 15 certain number of cooled bars onto the roller delivery bed 2.

To adapt the device for the handling of rolled flat bars, the following additional elements are provided.

20 At 19 in Figs. 2 and 5 is shown a shaft on which are fulcrumed glide-elements 20, which can be swung from their inoperative position shown by the broken line 20' in Fig. 4 to the full-line position in which they cover 25 the stepped plate 16. Fulcrumed on the same shaft 19 are the above mentioned stacking elements 13, which normally occupy the full-line position shown in Fig. 4, from which position they may be swung to the elevated position 13' as indicated by the broken lines in 30 Fig. 4. At 21 in Figs. 2, 4, and 5 are shown movable stops corresponding in width to the distance between two adjacent removal members 3, which stops are so shaped and 35 designed as to afford a support to the rolled flat bar, as the stacking operation is commenced, and to maintain said support while the rolled flat bars are gradually moved across the cooling bed. Directly adjoining 40 the removal element 3 at the delivery end of the cooling bed 4 are plates 22 which may be formed integral with the roller delivery bed and are designed to receive the stops 21, when the entire cooling bed is covered in its 45 entire width with rolled bars. In that case the stops 21 have reached their position of rest indicated in Fig. 2 by the reference numeral 21'.

50 The rolled flat bars are shown in their various positions in Figs. 4 and 5 by the reference numerals 22, 22', 22'' at the beginning and end of an operation. At 24 in Fig. 5 is more clearly shown the manner of stacking the rolled flat bars.

55 When rolled flat bars shall be handled by the herein described device, the lever arms 6 are uncoupled from shaft 5 and in their place, the lever arms 7 shown in Figs. 2 and 5 are coupled with shaft 5, which two operations 60 can be performed by any well-known coupling and uncoupling means which are, therefore, not shown. By the uncoupling of the lever arms 6 also the lifting members 8 are disconnected, or made inoperative, whereas 65 the stacking devices 13 are now operatively

connected with shaft 5 by means of the links 12 and lever arms 7. The guide-shaft 11 remains entirely at rest, while rolled flat bars are handled, but the glide-members 20 are swung about the shaft 19 from their inoperative position shown by the broken lines in Fig. 4 to the full-line operative position shown in Fig. 4, and the device is now ready for the handling of rolled flat bars. The operation 70 is as follows:

The rolled flat bars shown at 22 in Fig. 4 are lifted in well-known manner from the feed-roller mechanism 1 to the position shown on the upper right hand in Fig. 4. When now through the rocking of shaft 5 the stacking elements 13 are moved from their inoperative position (full-line position in Fig. 4) to their operative position (broken lines in Fig. 4) then the rolled flat bar 22 will slide down from the position shown on the upper right hand in Fig. 4 to the position indicated at 22' where it comes to rest against the stop 13'' provided on the stacking elements 13. As the latter descend, the stop 13', which may be made an integral portion of the stacking element 13 or can be formed as a separate ledge, disappears below the inclined faces of the glide elements 20 thereby enabling the flat bar to glide down further from its position shown at 22' to the position shown at 22'' 90 shown in Fig. 5, where it arrives at the stop 21 at the beginning of the cooling bed 4. When during the next operation the stacking members 13 are again raised, the flat bar which has previously slid down to the position shown at 22'' in Fig. 5 is pressed against the stack of flat bars shown in Figs. 4 and 5, whereby the stack is moved ahead along the cooling bed 4 toward the left in Fig. 4. Each time, the operation just described is repeated, the stack of flat bars on the cooling bed is increased, until the entire cooling bed is covered by flat bars and the stop 21 arrives in its position of rest shown at 21' in Fig. 2. 95

The stacked flat bars are then removed 100 from the cooling bed in any well-known manner.

The advantage of my device consists in this that it is equally well adapted to two different methods of cooling rolled bars with the aid of the very simple means. Also provision is made that the large heat radiation of the rolled bars onto the parts of the device has no effect on its absolutely safe operation. 115

120 Preferably the inclined face 15 of the feed roller mechanism is provided with short metal pieces to support the rolled bars at spaced points, thereby to insure against warping of the comparatively long channel element of the feed roller mechanism by the heat of the rolled bars.

I claim:

1. Cooling means for rolled bars comprising, in combination, a feed mechanism for the 125

rolled bars, a cooling bed, a stepped member between the feed mechanism and the bed, means cooperating with said member to effect a step by step advance of bars entirely thereacross from the feed mechanism to the cooling bed, and a glide member separate from said means, said glide member being mounted for movement between an inoperative position in which it does not affect the step by step advance of the bars across the stepped member and an operative position in which it overlies the stepped member and extends from the feed mechanism to the bed to support bars during their transfer from the feed mechanism to the cooling bed.

2. Cooling means for rolled bars comprising, in combination, a feed mechanism for the rolled bars, a cooling bed laterally spaced from the feed mechanism, means for advancing bars step by step entirely across the space between the feed mechanism and the bed, and means separate from said first mentioned means for advancing bars over said first mentioned means entirely from the feed mechanism to the bed.

3. Cooling means for rolled bars comprising, in combination, a feed mechanism for the rolled bars, a cooling bed laterally spaced from the feed mechanism, a stepped member between the feed mechanism and the bed, means cooperating with said member to effect a step by step advance of bars thereacross from the feed mechanism to the cooling bed, a glide member separate from said means, said glide member being mounted for movement between an inoperative position in which it does not affect the step by step advance of the bars across the stepped member and an operative position in which it overlies the stepped member and extends from the feed mechanism to the bed to support bars during their transfer from the feed mechanism to the bed, and means cooperating with said glide member when the same is in its operative position to effect transfer of bars from the feed mechanism over the stepped member to the bed.

4. In combination with a feed mechanism for rolled bars and a cooling bed laterally spaced from said feed mechanism, means to effect transfer of bars from the feed mechanism to the bed comprising a bar supporting glide member between the feed mechanism and the bed inclined downwardly from the former to the latter, a cooperating bar feeding member mounted for rocking movement between positions above and below said glide member, and stop means on said feeding member effective to arrest downward sliding movement of a bar over said member when the same is rocked to a position above the glide member to lift the bar from the glide member and also effective when the feeding member is rocked to a position above the

glide member to effect edgewise stacking of a previously arrested flat bar onto the bed.

5. The combination as set forth in claim 4 in which the stop means on the feeding member comprises a formation of inverted V-shape disposed to extend above the top of the bed when the feeding member is moved to a position above the glide member and to occupy a position to permit a previously arrested bar to slide over the glide member onto the bed when the feeding member is moved to a position below the glide member.

6. In combination with a feed mechanism for rolled bars and a cooling bed laterally spaced from said feed mechanism, means to effect a step by step transfer of bars from the feed mechanism to the bed, and other means for transferring bars over said first mentioned means from the feed mechanism to the bed, said bar transfer means having a common operator with which the respective means are selectively connectible.

7. In combination with a feed mechanism for rolled bars and a cooling bed laterally spaced from said feed mechanism, a stepped member between the feed mechanism and the bed, a second stepped member for cooperation with said first mentioned stepped member, means for moving the second mentioned stepped member above the first mentioned stepped member to lift the bars from the first mentioned stepped member and for subsequently moving the second mentioned stepped member below the first mentioned stepped member to deposit the bars on the latter member, and means for imparting lateral movement to the second mentioned stepped member to effect a step by step advance of the bars across the members from the feed mechanism to the bed, said last mentioned means comprising a rock shaft, a lever arm rigid therewith, and a connection between said lever arm and the second mentioned member whereby the latter member is vertically movable relative to the lever and whereby rocking movement of the lever arm imparts lateral movement to said second mentioned member.

8. The combination as set forth in claim 7 in which there is a pin and slot connection between the lever arm and the second mentioned member.

In testimony whereof, I affix my signature.
JOSEF GASSEN.
